UNITED STATES PATENT OFFICE.

NOBLE Z. SMITH, OF PEORIA, ILLINOIS.

ATTACHMENT FOR VAULT DOORS.

Application filed April 17, 1922. Serial No. 553,412.

REISSUED

To all whom it may concern:

Be it known that I, NOBLE Z. SMITH, a citizen of the United States, residing at Peoria, in the county of Peoria and State of Illinois, have invented new and useful Improvements in Attachments for Vault Doors; and I do hereby declare that the following is a full, clear, and exact description of the invention, which will enable others skilled in the art to which it appertains to make and use the same.

This invention pertains to an attachment for vault doors.

An object of my invention is to provide means by which the door of a bank vault or other similar place may be prevented, on occasion, from being wholly closed and by which in the attempt to close said door will be automatically locked or latched in its partially closed position and made immovable from the outside.

Another object is to provide an attachment for the door of a bank vault having for its purpose to aid in frustrating attempted banditry, and by which the operatives in places having a vault may be safe from molestation after entering said vault, and yet may use the said vault as a vantage point from which, by the use of fire arms, to deal with outlawry and prevent loss of valuables.

Still another object is that of so arranging and organizing parts on the door of a vault that operatives of the institution in which the vault may be installed, whether having taken refuge in said vault or having been forced into it, may have control of the said door preventing its being wholly closed or of being swung open from the outside after an attempt to close it, to the end that from within the vault such parts may be operated to permit the door to be opened for giving such operatives an advantage in the use of fire arms, while admitting of quickly closing and latching said door in an ajar position.

To the end that the structure used and the purpose thereof may be more fully understood, I have provided the accompanying drawings forming part hereof, it being understood that I do not limit myself to the structure illustrated since various changes are possible while still within the scope of the invention and the claims herein.

Figure 1 is an elevation of the inner side

of a vault-door showing my invention installed thereon.

Figure 2 is a plan of the upper edge of a vault-door with my invention shown installed on a ledge thereof.

Figure 3 is a similar figure showing certain parts in different positions from those shown in Figure 2.

Figure 4 is also a plan of the top edge of a door showing altered positions of parts illustrated in Figure 2, and

Figure 5 shows, in perspective, part of the door and parts of my invention mounted thereon.

Parts of the front wall of a vault are designated in Figures 1, 2 and 3 by the character 1, which constitute the door-jamb, while 2 is the vault-door, 3 being a ledge at the top of the latter through which the usual locking bolts 4 extend.

Lying in the angle formed by the door 2 and the ledge 3, Figure 5 especially, is a bar 5 adapted to shift in the direction of its length. Said bar may be placed elsewhere on said ledge but the position shown is a convenient one since a natural guide is created by these parts. As a convenient manner of retaining the bar in position while permitting the longitudinal movement referred to, a block 6 is secured upon the ledge 3, an extension thereof lying within a groove 7 in said bar.

One end of the latter extends beyond the hinged edge of the door and abuts upon the door jamb, being there held elastically by suitable means such, for example, as a spring 8 attached at one end to the door and at the other to the said bar.

A slide 9 is likewise placed in the angle formed by the door 2 and the ledge 3, the same adapted to project from or to be extended beyond the opposite edge of the door.

Said slide at its other end lies against the bar 5, forming a guide therefor, there being blocks 10 and 11, for example, on the ledge 100 which enter grooves 12 in the slide serving to retain the latter in place while permitting an endwise movement thereof to be explained.

13 is a recess in the slide into which the bar 5 is permitted to pass at times, there being a trigger 13' within the recess pivoted to said slide, its free end extending in the general direction of the said bar 5. A spring 14 serves to hold the trigger elas-

2
tically in the path of the bar while a control member 15 admits of manually moving the same out of said path, or from the position of said trigger in Figure 2 to that shown in Figure 4, to permit the bar to move behind it into said recess.

5' is a recess in the bar 5 into which a pin 9' carried by and slidably within the slide 9 is adapted to enter, said recess having an 10 inclined inner wall surface for ejecting the pin.

Pivottally mounted upon the ledge 3 is a latch 16 which in the present instance is adapted to swing in a horizontal plane and 15 may occupy one of two extreme positions, i. e. that shown by dotted lines in Figure 2 and as in Figure 3, but in use moving between these two positions as will appear presently.

20 Said latch has a projecting heel portion 17 near its pivoted end with which an extension 18 of the slide 9 is adapted to engage, whereby in the longitudinal shifting movement of the latter said latch will be 25 swung upon its pivot.

Depending from the ceiling or other convenient part of the interior of the vault, is a stop or keeper 19, Figures 1 and 3, with 30 which said latch is adapted to cooperate when the door is moved toward its closed position under circumstances now to be disclosed.

Normally, the parts lie in the positions shown in Figure 2 whether the door is standing ajar or wide open, but when wide open 35 (not shown) the bar 5 will be extended from the door-edge still farther, due to the pull of the spring 8 and will rest upon a cam 1' on the wall 1, which cam will serve to gradually move the bar by forcing it lengthwise toward the trigger.

When and as the door is moved in an attempt to close it, either by bandits to imprison persons driven into the vault, or by 45 persons who may have entered for safety, the bar 5 will be forced against and cause the trigger 13' to be shifted with it together with the slide 9. The latter will be thereby projected at its outer end beyond the edge 50 of the door to strike the jamb as in Figure 3, preventing the door being closed. As this action occurs the latch 16 will have been swung from the dotted line position, Figure 2, to that shown in Figure 3 against the 55 depending stop or keeper 19.

Those from without are thus now unable to either tightly close the door due to the projecting slide 9 which, of course, cannot be inwardly shifted, nor can they open the 60 door due to the fact that the latch 16 will engage said bar or keeper 19 and prevent it. Neither can the door be opened sufficiently to permit the entrance of any instrument to reaching the said latch 16, nor could 65 the latch be moved, even if reached, to dis-

engage it from the said keeper from the fact that the heel portion 17 lies against the now immovable slide 9 held by the bar 5 and trigger 13'.

However, a person within the vault when 70 opportunity permits, may move the trigger away from the bar 5 to permit it to move past the latter, Figure 4, whereupon the slide 9 may be shifted by the latch, as that member is moved away from the keeper 19, 75 sufficiently to permit the door to be opened.

As danger threatens, the latch is thrown 80 against the keeper and the slide moved outwardly again to permit the trigger to again take up its position behind the bar 5.

Thus it is seen that those from without 85 are at the mercy of firearms used by those protected within the vault. An advantage also in the use of my device is that persons cannot be locked within a closed vault and thus be in danger of suffocation, as often results.

When locking the vault for the night the trigger 13' is withdrawn from behind the bar 5, as already explained, so that the latter may pass behind it. Now by pushing the pin 9' into the recess 5', as shown in Figure 4, the bar is held behind the trigger in opposition to the pull of the spring 8 preventing the said trigger being released. With 90 the slide 9 withdrawn so that its end is inward from the edge of the door the latter may now be closed, the bar 5 being naturally and necessarily pushed farther behind the trigger during which action the pin is forced 95 outward and out of the recess 5' so that when the door is again opened for the day's business the bar can move from behind the trigger, the device being automatically set ready 100 for an emergency.

I am unaware of an attachment for a vault door having the aim and purposes outlined herein, and therefore having set forth a type 105 of mechanism for accomplishing these aims, I claim:

1. In combination with the mounted door of a vault and the door-jamb, of mechanism movable in and during the act of moving the door to its closed position, the same adapted to engage at one end a relatively immovable part during said act whereby to 115 carry the other end of said mechanism between the door-jamb and an edge of the door for preventing entirely closing the latter.

2. In combination with the door and a door-jamb of a vault, of mounted mechanism operated automatically in the act of moving the door to its closed position by contact with a relatively stationary portion for projecting said mechanism between an edge of the door and said door-jamb, a keeper within the vault, and a latch operated automatically by said mechanism to engage said keeper.

3. In combination with the door and

door-jamb of a vault, of mounted mechanism inward from the outer face of the door operated automatically in and due to movement of the latter to a partially closed 5 position for moving a part of said mechanism between an edge of the door and the door-jamb, preventing said door being entirely closed, and means within the vault to automatically latch the door and prevent its 10 being opened from the outside when moved to said partially closed position.

4. In combination with the door and door-jamb of a vault, of mechanism carried on the inner side of the door mounted to move 15 parallel to the plane thereof including a part adapted to engage the door-jamb at the hinged edge of the door and also including a part adapted to be projected from the opposite edge of the door when and as the 20 door is moved toward its closed position, and means to automatically latch the door and prevent the movement thereof from the outside to open it when in a partially closed position.

25 5. In combination with the door and door-jamb of a vault, of two separate parts mounted on the door capable of movement relatively to each other and relatively to said door, one of them normally and elastically abutting against the jamb at the 30 hinged edge of the door, the other adapted to be projected beyond the other edge of said door to prevent entire closing of the door, a member adapted for operative engagement with both parts whereby movement of one will impart movement to the other, a latch operated by one of the parts in its movement, and a keeper within the 35 vault with which the latch is adapted to engage when the door is stopped by the projecting part.

40 6. In combination with the door and door-jamb of a vault, of mechanism mounted on the door including a part adapted at 45 one end to abut against the jamb, means to elastically hold the same against said jamb, a second part adapted for movement with respect to the first, and a trigger pivoted on

one of the parts adapted to operatively engage the other by which the movement of 50 one will impart movement to the other, the trigger adapted to be moved to permit the parts to move relatively.

7. In combination with the door and door-jamb of a vault, of mechanism mounted 55 on the door including a part adapted at one end to abut against the jamb, means to elastically hold the same against said jamb, a second part adapted for movement with respect to the first, and a trigger pivoted on 60 one of the parts adapted to operatively engage the other by which the movement of one will impart movement to the other, the trigger adapted to be moved to permit the parts to move relatively, and means to control the elastically held part with respect to 65 said trigger.

8. In combination with the door of a vault or other enclosure, of mounted mechanism adapted to be operated by the door in 70 the act of moving said door toward its closed position to automatically project a part of such mechanism into the path of the said door to stop the same in an ajar position, and means to automatically latch 75 the door in that position to prevent its being opened from the outside.

9. In combination with the door of a vault, of mounted mechanism adapted to be operated through the instrumentality of 80 said door and including a part to be moved into the path of said door in an attempt to close the same to stop it in an ajar position, said part adapted to be moved manually relatively to the mechanism, and means to 85 automatically latch the door after having been moved to such ajar position to prevent said door being swung open from the outside.

In testimony whereof I affix my signature 90 in presence of two witnesses.

NOBLE Z. SMITH.
